[57] CLAIM

The ornamental design for a rotating rear view truck mirror, as shown and described.

DESCRIPTION

FIG. 1 is a perspective view from the left side of the rotating rear view truck mirror showing our new design;

FIG. 2 is a right side elevation view thereof;

FIG. 3 is a front elevation view thereof;

FIG. 4 is a rear elevation view thereof;

FIG. 5 is a top plan view thereof; and

FIG. 6 is a bottom plan view thereof.

The broken line showing of a support bracket in FIG. 1 is for illustrative purposes only and forms no part of the claimed design.

FIG. 1

FIG. 2

FIG. 3

FIG. 4

FIG. 5

FIG. 6
